ROTATABLE INGOT MOLD

Albert H. Jung, Flushing, N. Y., assignor to United American Metals Corporation, Brooklyn, N. Y., a corporation of New York

Application July 8, 1939, Serial No. 283,484

9 Claims. (Cl. 22—139)

This invention relates to molding apparatus and more particularly to fluid cooled dumping molds.

Prior to the instant invention it has been customary to provide fluid cooled molds which were relatively difficult and expensive to manufacture and generally unsatisfactory with regard to operation because of inefficient fluid connections, bearings, and fluid distribution.

10 These prior molds have been of such configuration that their manufacture by casting or by other relatively inexpensive methods of fabrication have not been feasible. Further, the designs of prior molds have involved such paths 15 of thermal exchange fluid flow as to contain inoperative or substantially inoperative portions wherein stagnation of the thermal medium may take place with corresponding inefficiency of the device.

20 In prior constructions involving rotating dumping molds, little attention has been paid to apparatus for conducting thermal exchange fluid from a stationary conduit to the rotary molds. The use of flexible conduits has been contemplated but such construction have not been found to be satisfactory as they are continually in the operator's way and make for inefficiency in operation.

25 Prior rotating dumping molds have not incorporated in their construction satisfactory yet inexpensive ingot receiving means which occupies substantially no room when not in use and acts to protect the floor upon which the mold stands and to guide the dumped ingots in an orderly and regular manner when in use as taught by the instant invention.

30 It is an object of the instant invention to provide a novel fluid cooled dumping mold of such configuration as to simultaneously lend itself to ready fabrication and provide for relatively efficient thermal heat exchange.

35 It is another object of the instant invention to provide a novel double-sided fluid cooled dumping mold involving a combined swivel connection and bearing.

40 It is a still further object of the instant invention to provide a twin set of double-sided fluid cooled rotating dumping molds including a novel dumped ingot receiving means.

45 Other objects and the nature and advantages of the invention will be apparent from the following description taken in conjunction with the accompanying drawings, wherein:

50 Fig. 1 is a view in perspective of a double-

sided twin set of rotating dumping molds in accordance with the invention;

Fig. 2 is a fragmentary detail vertical sectional view of one form of combined swivel pipe connection and bearing incorporated in the dumping mold illustrated in Fig. 1;

Fig. 3 is a horizontal sectional view taken on line 3—3 of Fig. 1 and looking in the direction of the arrows;

Fig. 4 is a vertical section of a single mold 10 section taken along line 4—4 of Fig. 3 and looking in the direction of the arrows;

Fig. 5 is a view similar to Fig. 2 but of a modified form of combined swivel pipe connection and bearings;

Fig. 6 is a fragmentary view in perspective of a thermal fluid distributor;

Fig. 7 is a front elevational view of a dumping mold incorporating telescopic dumped ingot receiving means; and,

Fig. 8 is an end elevation of the mold illustrated in Fig. 7 but with the telescopic dumped ingot receiving means in the "in" position.

Referring to the drawings, a framework 10 may generally comprise a series of pipes 11 joined by connectors 12 to form a substantially rectangular structure. From the connectors 12 there extend vertical pipes 13 and roller supports 14 whereby the entire mold apparatus may be readily moved about at the convenience of the operator. A pair of T section lengths of structural steel 15 extend across the upper front and rear portions of the apparatus and involve the dual function of supporting the swivel connector bearings 16a, 16b, 16c and 16d, see Figs. 1 and 3, and engaging the stops 17 mounted on the front end of the rotatable molds 18 and 18a respectively. The T-section lengths 15 are secured to the upstanding pipe members 13 by the threaded caps 20 which engage corresponding threaded upper portions of the pipes 13 extending through the T section lengths 15. Mounted substantially centrally of the stops 17 are the handles 21 whereby the operator may rotate the molds 18 as desired in accordance with casting activity.

The combined conduit swivel and bearing 16a may be connected to a conduit 22 leading from a source, not shown, of cooling fluid such as cooling water. Associated with the cooling fluid entrance inside of the mold 18a and the discharge side of the swivel connector 16a is the distributor 23, illustrated in detail in Fig. 6 and comprising a pipe-like element closed at its end 24 but pierced as at 25 as well as through the cylindrical surface 55

surface 26 adjacent the end 24 by the series of holes 27 which are arranged completely thereabout whereby a discharge takes place, as indicated by the arrows in Fig. 3, to insure uniform distribution of cooling fluid and to obviate stagnation thereof.

After the cooling fluid, such as cooling water, has passed through the channels 28 of the mold 18a to effectively cool the cavities 29 and 29a, it is discharged through the opening 30 associated with the swivel connections 16b from whence it is led through connecting pipe 31, which may simply comprise a rubber hose strapped to fittings 32 and 33 by clamps 34, see Fig. 1, to the swivel bearing 16c which may be similar to 16a and include a distributing member 23a which serves to distribute the heat absorbing fluid through the channels 35 in mold 18 in a manner similar to the distribution through the channels 28 in mold 18a.

After the cooling medium is passed through the channels 35 it is collected in the far end of the mold 18 and discharged through the opening 36 which is associated with the swivel connector 16d which is connected to a pipe 37 which in turn may be connected with the sewer or other suitable vessel or tank, not shown.

The mold cavities 29, 29a of the mold 18a may be similar and of generally trapezoidal section. 30 The fluid passage 28 may be generally hexagonal in section as best illustrated in Fig. 4. The cavities 29 and 29a may have a common bottom wall 38 of a thickness generally corresponding to that of the side walls of the cavities which are sloped 35 as shown to provide draft which is essential to the casting of the ingots in the mold cavities and is also so shaped, in accordance with the invention, to provide draft for the casting of the mold itself. The mold 18 is adapted to be cast 40 in a two part mold including destructable cores which serve to form the passages or channels 28. These destructable cores are adapted to be removed through openings with which the swivel connections are associated and the openings 39 45 which may be subsequently tapped and plugged by plugs 40, see Fig. 1, upon completion of the mold casting.

To provide for the ingress and egress of heat exchange fluid to the rotating mold a swivel joint such as illustrated in Fig. 2 may be utilized. The stationary pipe 22 may pass through a notch 41 in the horizontal portion 42 of the T section lengths 15 and be associated with the angular connector 43 which in turn is threaded to stationary pipe section 44 provided with an angular ring 45 adapted to be engaged on both sides by packing 46 which also may be in the form of rings. The gland 47 may be formed integral with the mold 18a and be capped by the packing screw plug 48 in threaded engagement with the interior of the wall 49 of the gland 47. A nut 50 may be utilized in threaded engagement with the exterior of the threaded portion of the cap 48 and the end of the walls 49 of the gland 47. It is to be borne in mind that the mold 18a is adapted to be rotated about the stationary pipe section 44 and that the angular ring 45 formed integral therewith serves to prevent the leakage of fluid transferred between the interior of the pipe section 44 and the passage 28, the ring 45 cooperating with the packing 46 in addition to the cooperation of the packing with the generally cylindrical exterior 51 of the pipe-like element 44.

75 A modified form of swivel connector bearing

75 A modified form of swivel connector bearing

is illustrated in Fig. 5, wherein is illustrated a gland 52 which may be independent of the mold casting 18 and comprises a body portion 53 and a packing nut 54 as well as packing rings 55 which cooperate with the rotatable element 56 having formed thereon the angular ring 57 which is drilled at 58 to provide communications with its interior 59 from the interior of the stationary pipe 22. The rotatable connector element 60 communicates the interior of the mold 18, that is, the passage 28, with the interior 59 of the element 56 and is threaded to the mold 18 and the element 56. 5 10

The combined swivel fluid connector and mold bearings illustrated in Figs. 5 and 6 are not only adapted to serve as passages for the thermal exchange fluid between the pipe exterior of the mold and the mold's interior, but they serve as supporting bearings for the rotating molds. Accordingly, the elements 16a, 16b, 16c and 16d are designed to be stress transmitting and to prevent leakage otherwise present because bearing stress tends to aggravate leakage tendencies due solely to fluid pressure in swivel joints. In accordance with the invention, leakage is prevented by the provision of an annular ring and the association and cooperation of packing with the sides of said rings in addition to the usual cooperation of said packing with the cylindrical exterior wall of the pipe section with- in the packing rings. In the embodiment illustrated in Fig. 5, the ring 45 is stationary. In the embodiment illustrated in Fig. 6, the ring 51 is rotatable and in addition it forms an inlet passage. This latter construction is adapted to be used in connection with molds which are specially cast to receive a swivel connection such as illustrated in Fig. 5.

As has been explained in detail above, the molds in accordance with the invention are generally superior to previous molds for they may be readily fabricated as by casting and permitting the flow therethrough of heat transfer without the use of movable flexible pipes. Further, special distributors are provided to insure substantially uniform distribution of the thermal exchange fluid through the interior of the heating exchange passages within the interior of the mold thereby preventing a stagnation and delay of solidification of ingots cast within the cavities of the molds. 40 45 50

In operation, the mold 18 after being filled may be rotated by grasping the handle 21 which may comprise a revoluble insulated part and imparting thereto an oscillatory motion, thereby effecting dumping of ingots solidified within one side of the mold. By this time, the mold 18a may be filled and ready for dumping and the handle of that mold is oscillated, effecting the emptying of one side of that mold. While the mold 18a is being dumped the second side of the mold 18 may be filled and when the filling operation of that mold is completed the second side of the mold 18a may be filled with molten metal to be cast into ingots. By the time the second side of the mold 18b is filled the mold 18a is again ready for dumping and the cycle described repeated.

The above method of operation is relatively efficient with regard to the utilization of the time of a single operator working on a double-sided twin mold such as illustrated in Fig. 1 and filling and casting may be substantially continuous. 70

In accordance with the invention, not only 75

does the hot molten metal within the cavities transfer its latent heat of fusion through the side walls thereof to the heat exchange cooling fluid, but the side walls of the bottom empty 5 cavities act as fins to also transmit heat from the side walls and bottoms of the filled cavities to the cooling fluid contacting the side walls of these empty cavities, whereby rapid cooling permitting rapid substantially continuous casting 10 may be effected.

Referring to Figs. 7 and 8, the water cooled dumping mold illustrated in Fig. 1 is here again depicted but includes, in addition to what is shown in Fig. 1, a telescopic cradle whereby 15 freshly cast ingots may be rapidly dumped without fear of breakage and with assurance that they will be guided regularly and orderly to an exposed platform from which they may be readily picked up for subsequent association with a 20 line type casting machine or for loading elsewhere as desired.

Connecting the T irons 15 which serve to support the rotating molds 18 and 18a through the combined swivel joints and bearings 16a, 16b, 25 16c and 16d, is the rod 70 secured to the vertical portions of the T irons 15 by the nuts 71 and 72 respectively. Bent in angular fashion over the rod 70 are a pair of stationary conveyor straps 73 and 74 having lower leg portions 75 and 76 30 which are bent over and secured to the frame members 11 by any suitable means as by spot welding. The conveyor straps 73 and 74 may also be secured to the rods 70 by any suitable means such as by spot welding.

35 The lower portions 75 and 76 of the conveyor straps have circular openings 77 therethrough, see Fig. 1, which are adapted to receive the ends of a pair of hollow cylinders 78 within which the cradle 79 is adapted to cooperate in telescopic 40 fashion. The ends of the hollow cylinder 78 are threaded to receive the nuts 80 on one side of the depending portions 75 and 76 and the guide cap 81 on the other side of the depending portions 75 and 76 whereby the hollow cylinders 78 45 will be securely held in place.

Each cradle 79 may generally comprise a pair of longitudinal pipe sections 82 capped at its inner end 83 to prevent entirely pulling out of the cradle from the hollow cylinder 78 and joined 50 at its opposite end by the connections 83' which cooperate with upstanding pipe or rod pieces 84 which act as stops. The connectors 83' also cooperate with relative short depending legs 85 which may be capped at their bottoms 86 in 55 order to effect a relatively great floor contact area. The diameter of the longitudinal pieces 82 is less than the diameter of the openings 87 within guide caps 81 and the internal diameter of the hollow cylinders 78 whereby when the 60 cradle 79 is pulled to its outward position as illustrated in the right hand portion of Fig. 7 and when the relatively short legs 85 are permitted to rest on the floor, the general plane of the cradle will be as indicated by the dot-dash line 88 which is angularly disposed from, and lower than, the true horizontal as indicated by the dot-dash line 89 which is parallel to the floor. When both cradles 79 are in the innermost position as illustrated, in the left hand portion of 65 Fig. 7, the entire mold may be wheeled about on the roller mountings 14 without interference.

It is to be noted that in accordance with the invention, the rotatable axes of the dumping mold sections 18 and 18a are off center with their 70 relatively short respective outside portions

adapted to be oscillated downwardly. This construction permits of a relatively steep angular disposition of the strap conveyors 73 and 74 without interference with the oscillation or rotation of the mold sections and yet permits of a 5 relatively large number of mold cavities.

In operation, upon rotation or oscillation of the mold section 18a, the freshly cast ingots are dumped in inverted position upon the strap conveyors 73 and 74 as illustrated by the ingot 10 90 which slides down the relatively steep strap conveyor 73 until it reaches the depending portions 75 and 76. The ingot 90 thereupon is again inverted to its normal cast position as shown by the ingot 91 resting on the longitudinal members 82 of the cradle 79 which are spaced apart by the hollow cylindrical member 78 and the rod or pipe end member 92 which is oscillated with the connectors 83.

It will be apparent from the above description 20 that relatively eccentric disposition of the mold sections cooperates with the relatively steep conveyor straps 73 and 74 to effect an efficient dumping and conveying equipment and further that the conveyor straps 73 and 74 involve an 25 additional function of supporting hollow cylindrical members 78 which act as a base for and cooperate telescopically with a pair of cradles 79 which are adapted to be extended in operative position resting upon the floor to insure re- 30 stricted collection and stacking of freshly cast ingots and when in innermost position are lifted off the floor permitting ready portability of the entire mold assembly upon the roller members 14. 35

It will be obvious to those skilled in the art that various changes may be made in this device without departing from the spirit of the invention and therefore the invention is not limited to what is shown in the drawings and described in the specification but only as indicated in the appended claims.

What is claimed is:

1. A double-sided rotatable fluid cooled mold comprising a mold section formed with a plurality of cavities on its top and bottom sides and provided with interspersed heat exchange fluid medium passages therethrough, said passages directly cooperating with the side walls of said cavities to remove heat therefrom, a set 50 of single walls being common to the bottoms of the cavities in the top side and the bottom side of said mold section, the cavities being generally trapezoidal in cross-section, the fluid passages being generally hexagonal in cross-section, a 55 combined swivel fluid connector and bearing associated with said mold section, said combined element involving an annular ring packed on both sides, a handle for said mold section, a stop formed integral with said mold section whereby 60 oscillatory motion of the mold section is limited, said handle associated substantially centrally of said stop whereby association of the handle with the rotatable mold section is effected, a fluid medium distributor associated with the interior 65 of said mold section, said distributor having discharge openings extending in directions correlated with the fluid passage to effect substantially uniform distribution of heat exchange medium therethrough and obviate stagnation, a 70 frame for directly supporting said swivel connector and thereby indirectly support said rotatable mold section, and said stop arranged to cooperate with said frame to limit the movement of said rotatable mold section. 75

2. Structure recited in claim 1, said mold section being mounted on a longitudinal axis located closer to one side of the section than to the other, whereby the short side may be rotated or oscillated in a downward direction with but relatively small clearance therebelow.

3. The structure recited in claim 1, said frame supporting said mold section in elevated position, a pair of metal straps secured to said frame 10 on an incline below said mold section to receive and convey freshly cast and dumped ingots.

4. The structure recited in claim 1, said mold section being mounted on a longitudinal axis being located closer to one of its sides than the other whereby the short side may be rotated or oscillated in a downward direction with but relatively small clearance therebelow, said frame supporting said mold section in elevated position, a pair of metal straps secured to said frame 20 on an incline below said mold section to receive and convey freshly cast and dumped ingots.

5. A double-sided rotatable mold comprising a mold section formed with a plurality of cavities on its top and bottom sides, a frame for supporting said mold section, said mold section being rotatably mounted in said frame along a longitudinal axis spaced closer to one side of said section than the other, a conveyor having an inclined section for said mold section secured 30 to said frame in operative position below said mold section, said conveyor comprising a pair of metal straps arranged in angular configuration to effect a slope, the inclined portion of said conveyor being arranged relatively close to the locus 35 of the short side of the rotatable mold section.

6. The structure recited in claim 5 and a telescopic cradle cooperating with said frame, said cradle having horizontal portions spaced from the lower portions of the frame which are adapted to rest upon the floor, said cradle having legs which are shorter than the distance from the floor to the horizontal portions thereof whereby when said telescopic cradle is in its innermost position the legs thereof do not touch the floor, said frame being mounted on wheels, the relation 45 between the cradle and the frame being such that when the cradle is in its outermost position the horizontal portions thereof may be inclined and the legs thereof touch the floor, whereby freshly cast and dumped ingots may be conveyed in 50 regular and orderly fashion to the cradle when the same is in its outermost position, and when the mold is not in use or its location is desired to be changed the cradle may be moved to its innermost position raising its legs off the floor and the mold pushed about on its wheels.

7. An integral double-sided fluid cooled mold adapted to be rotated or oscillated for dump-

ing comprising a unitary casting having a plurality of cavities in its top and bottom sides and provided with interspersed heat exchange fluid medium passages therethrough, said passages directly cooperating with the side walls of said 5 cavities to remove heat therefrom, a set of single walls being common to the bottoms of the cavities in the top side and the bottom side of each mold section, the cavities being generally trapezoidal in cross section and of a height generally corresponding to the height of said mold, the fluid passages being generally hexagonal in 10 cross section, a plurality of plugged openings in the exterior side walls of said mold, whereby the same is adapted to be fabricated by casting 15 in a two-part mold with destructible cores which may be removed through the openings in the side walls thereof, the trapezoidal section of said cavities providing draft for the casting of said mold as well as draft for the casting of ingots in said 20 cavities.

8. A mold comprising a rotatable dumping mold section, a frame for supporting said section, a conveyor mounted therebeneath, a telescopic cradle associated with said frame and cooperating 25 with said conveyor when in its outermost position, said frame comprising a pair of hollow cylinders extending laterally thereof, said cradle comprising a pair of laterally extending members cooperating with said cylinders, the external 30 cross sectional dimension of said laterally extending members being less than the internal dimension of said laterally extending cylinders, said cradle comprising a cross member, a pair of upstanding stop members and a pair of relatively 35 short depending legs, the length of said legs being less than the height of said cylinders above the bottom of said frame, means for preventing said cradle from being detached from said cylinders when said cradle is pulled to its outermost 40 position, said cradle being adapted to be entirely above the floor when in its innermost position and adapted to have its legs rest upon the floor when in its outermost position with its lateral members arranged in a plane at a slight 45 angle to the horizontal.

9. A double-sided rotatable ingot mold, a frame for supporting said mold in rotatable relation, the axis of rotation of said mold being longitudinal thereof but closer to one side than the other, whereby the short side may be rotated in a downward direction with but relatively small clearance therebelow, and an inclined conveyor arranged below said rotatable mold and relatively close to the locus of the short side of the 55 rotatable mold.

ALBERT H. JUNG.
